CHASER HOLDING MEANS

David R. Powell and William L. Moore, Cleveland, Ohio, assignors to The National Acme Company, Cleveland, Ohio, a corporation of Ohio

Application August 19, 1943, Serial No. 499,173

10 Claims. (Cl. 10—103)

This invention relates to threading tools such as taps and dies and, more particularly, to an improved means for holding the chasers and chaser blocks in position in the die body, the principal object being the provision of such holding means which is simple in construction, inexpensive to manufacture and efficient in use.

Heretofore, the chasers and chaser blocks have been placed in position in the die body with no means for holding them in position other than the die cap or housing and when it was desired to move this die cap out of its holding position for the purpose of removing the chasers, or for any other reason, the chasers and blocks frequently would fall out of the die body and this often resulted in damage thereto.

Therefore, an object of the present invention is the provision of means for holding the chasers in place in the die body independent of the die cap or other operating parts in such manner that they may be readily removed and reinserted when desired without the necessity of removing the holding means and which will not in any way interfere with the normal action of the die.

In the drawing accompanying and forming a part of this specification,

Fig. 1 is a partial plan view of a die head, illustrating this improved holding means in position, and

Fig. 2 is an end view thereof, partly in section. Similar characters of reference indicate corresponding parts in the several views.

Before explaining in detail the present improvement and its mode of operation, we desire it understood that the invention is not limited to the details of construction and arrangement of parts which are illustrated in the accompanying drawing since the invention is capable of other embodiments, and that the phraseology employed is for the purpose of description and not of limitation.

This invention is an improvement upon the dies and taps of The National Acme Company and particular reference may be had to the patent to William J. Hogg, No. 1,952,205, for a complete understanding of the general construction and operation of such die and only so much of the die head has been illustrated herein as is thought necessary for an understanding of the present invention.

The die body 2 is provided with a cap or housing 3 usually shiftable on the die body for opening and closing the chasers and this housing 3 may be shifted back to the position shown in Fig. 1 of the drawing when it is desired to re-

move the chasers and blocks from the die body. Heretofore, when the housing was shifted to this position, as hereinbefore pointed out, frequently the chasers would fall out of the die body.

5 The front face of the body 2 is provided with a plurality of chaser receiving slots or recesses 4 of T-shape for the reception of one-piece, stepped, correspondingly-shaped chaser blocks 5 to which may be secured in any suitable manner

10 the chasers 6.

Each chaser block is provided with a rearwardly extending pin 7 projecting into a circularly formed slot 8 in the rear of each T-shaped slot 4 of the die body. These slots are each provided with a spring 9 and a headed plunger 10 located in position to engage the rearwardly extending pin of the chaser blocks and are for the purpose of shifting the chaser blocks and chasers outwardly to hold the cam faces in engagement with the cams of the cap and also to open the chasers when the cap is withdrawn.

Located to one side of each circular opening 8 is a threaded opening 11 for the reception of a headed screw 12, the head of which is intended slightly to overlap the opening 8 in order to maintain the spring 9 in the opening when the chasers are removed.

A spring clip 13, which may be of any suitable shape adapted to project or extend into the opening 8, is held in place by the screw 12 and slightly engages the pin 7 of the chaser block in such manner that it will yield to permit insertion and removal of the chaser blocks when slight additional pressure is exerted on them but will hold 35 the blocks in the body when the cap or housing 3 does not engage them. In other words, this spring is a supplemental holding means for holding the chasers in position on the release thereof by the die cap and is, in a sense, a latch-like holding means for such chasers.

40 Thus, it will be seen that the provision of this spring clip will act to prevent the chasers from falling out of the die body regardless of the position of the cap or housing and will not in any way interfere with the intended operation of the die and its parts. The clip is not inserted deeply enough into the opening 8 to interfere in any way with the action of the spring 9.

45 It is to be understood that by describing in detail herein any particular form, structure or arrangement, it is not intended to limit the invention beyond the terms of the several claims or the requirements of the prior art.

Having thus explained the nature of our said 50 invention and described a way of constructing

and using the same, although without attempting to set forth all of the forms in which it may be made or all of the modes of its use, we claim:

1. A threading tool having a body, removable chasers carried by said body, operating means for said tool adapted to hold said chasers within the body, resilient means for urging the chasers outwardly and means extending transversely of said resilient means for holding the chasers in said body independent of the operating means of said threading tool, said transversely extending means effective to permit removal of said chasers while maintained in normal position in the body.

2. A threading tool having a body, removable chasers carried by said body, operating means for said tool adapted to hold said chasers within the body, resilient means for urging the chasers outwardly; and resilient means extending transversely of said first resilient means for holding the chasers in said body independent of the operating means of said threading tool.

3. A threading tool having a body, a plurality of slots therein, chaser carrying blocks removably carried in said slots, means for holding said blocks in the body, means for urging the chasers outwardly, and latch-like means carried by the body and having engagement with said blocks for holding the chasers in said threading tool upon the release of said first holding means.

4. A threading tool having a body, a plurality of slots therein, chaser carrying blocks removably carried in said slots, means for holding said blocks in the body, means for urging the chasers outwardly, and latch-like means carried by the body and having engagement with said blocks for holding the chasers in the body and in position to permit insertion and removal of said blocks without removal of said latch-like means, said last means comprising a spring clip extending transversely of said outwardly urging means and operative on the release of said first holding means.

5. A threading tool having a body, removable chasers carried by said body, shiftable means cooperating with the body and chasers for opening and closing the chasers and permitting their removal, means for urging the chasers outwardly, and resilient means comprising a member projecting transversely of said outwardly urging means carried by the body for holding the chasers therein independent of said shiftable means.

6. A threading tool having a body, removable chasers carried by said body, shiftable means cooperating with the body and chasers for opening and closing the chasers and permitting their removal, resilient means for urging the chasers outwardly and resilient means extending trans-

versely of said first resilient means carried by the body for holding the chasers therein independent of said shiftable means, said resilient means adapted to permit removal and insertion of the chasers without removal of said resilient means.

7. A threading tool having a body, removable chasers carried by said body, operating means for said tool adapted to hold said chasers within the body, resilient means for urging the chasers outwardly, and resilient means extending transversely of said first resilient means and also carried by the body in the rear of the chasers for holding the chasers therein independently of the operating means of said threading tool and effective to yield to permit the insertion of the chasers without manual operation of said second resilient means.

8. A threading tool having a body, a removable chaser carried by said body, a housing for normally holding the chaser in working position and operative to release and permit the removal of the chaser, resilient means for shifting the chaser, and supplemental resilient means engaging a part of the chaser for holding it in position against dropping out on the release of the chaser by the housing and effective to yield and permit the insertion of the chaser without manual operation of said supplemental means.

9. A threading tool having a body, a removable chaser block carried by said body and having a pin, a chaser carried by said block, means for normally holding the block and its chaser in working position and operative to release and permit the removal of the block and its chaser, means for shifting the chaser, and supplemental resilient holding means engaging the pin of the block for holding the block and its chaser in position on the release thereof by said first means and effective also to yield and permit insertion of the chaser and its block without manual operation of said supplemental means.

10. A threading tool having a body, removable threading means carried by the body and having a pin, a housing for normally holding the threading means in working position and operative to release and permit the removal of said threading means, resilient means for shifting the threading means, and supplemental resilient means comprising a spring clip having a part thereof extending over said pin to hold the threading means in position against dropping out on the release thereof by the housing and effective to yield and permit the insertion of the threading means without manual operation of said spring clip.
